F. W. MEYER,
TRUNK LOCKING DEVICE,
APPLICATION FILED AUG. 27, 1921.

1,412,564.

Patented Apr. 11, 1922.

Inventor
Frank W. Meyer
by C. G. C. Atty.

UNITED STATES PATENT OFFICE.

FRANK W. MEYER, OF OSHKOSH, WISCONSIN, ASSIGNOR TO THE OSHKOSH TRUNK COMPANY, OF OSHKOSH, WISCONSIN, A CORPORATION OF WISCONSIN.

TRUNK LOCKING DEVICE.

1,412,564.

Specification of Letters Patent. Patented Apr. 11, 1922.

Original application filed February 14, 1921, Serial No. 444,664. Divided and this application filed August 27, 1921. Serial No. 495,995.

To all whom it may concern:

Be it known that I, FRANK W. MEYER, a citizen of the United States, residing at Oshkosh, in the county of Winnebago and State 5 of Wisconsin, have invented new and useful Improvements in Trunk Locking Devices, of which the following is a specification.

This invention relates to locking devices 10 for wardrobe trunks, and more particularly to locking devices for wardrobe trunks for land or sea travel, as set forth in my co-pending application Serial No. 444,664, filed February 14, 1921, and of which the present 15 application is a division.

In the accompanying drawings—

Fig. 1 is a perspective view of a wardrobe trunk of the kind mentioned, standing upright on one end, closed and locked by a 20 locking device constructed in accordance with my invention;

Fig. 2 is a perspective view of the trunk unlocked and open, when used like a wardrobe trunk;

Fig. 3 is an enlarged longitudinal sectional view taken through trunk when lying on one side with its lid opened, as when the trunk is used under a berth or bunk of a steamship; and

Fig. 4 is an enlarged fragmentary vertical sectional view of the locking mechanism for the lid, taken on line 4—4 of Fig. 1.

The trunk shown in the drawings is constructed along the general lines of a center 35 opening wardrobe trunk. It has two hinged together sections 1 and 2, both of which are open at their upper ends. To close these ends, when the sections 1 and 2 are closed, I provide a lid 3 hinged to the section 1 at 40 the upper edge of its rear wall and extending over and closing the open ends of both sections when the lid is closed, as shown in Fig. 1.

The section 2 constitutes the wardrobe 45 section of the trunk and has side cleats 4, 4 extending the full length or height of the section and forming with the trunk walls a channel to receive a rectangular tray 5 provided with extensible trolleys 6 for garment hangers 7. This tray also has a clothes retainer 8 and the usual fixtures associated therewith. The tray 5 has a length and width substantially equal to the like dimensions of the section 2 and is slidably mounted

in said section. The latter having an open 55 end permits the tray to be drawn endwise therefrom and to be slid back into the section through the open end when replacing the tray in the trunk. To facilitate withdrawing the tray 5 from the section 2, the 60 tray is provided at its upper end with a pull tab 9 in the form of a loop to permit grasping thereof and also allowing the tray to be hung up on a hook or nail in a closet or room when it is out of the trunk. Sliding 65 of the tray from the section 2 is done when the trunk is lying flatwise on one of its sides and under a ship's berth, as fully set forth in my said copending application, and as indicated in Fig. 3 herein. 70

In the other section 1 is arranged a plurality of box like containers 10, 11, and 12. When the trunk is standing upright on its lower end, as shown in Figs. 1 and 2, these containers are one above the other with 75 the container 10 uppermost and accessible while in such position through the open upper end of the section 1. This container 10 has a hinged lid 13 in its top wall to enable access to be had to the interior of 80 the container without drawing it out of the section 1. To prevent the container 10 from sliding out of the open side of the section 1, I provide a cross-bar 14 extending across the section at its upper end and secured to 85 the side walls thereof, as shown in Fig. 2. The two lower boxes or containers 11 and 12 may be withdrawn through the open side of the section 1 when access is to be had to the interior thereof while the trunk is standing upright and used like an ordinary wardrobe trunk. When the trunk is under a ship's berth and lying on one side, as shown in Fig. 3, the containers 10 to 12 are removed from and replaced in the trunk by sliding 90 95 them into and out of the open end of the section 1, all as fully set forth in my said copending application.

Located inside of and secured to one of the side walls of the section 1 are a plurality of fixed locking members or eyes 15. These project into the other section 2 through apertures or slots 16 in one of the side cleats 4 of the section 2 when the trunk sections are closed together. At this time 100 105 the fixed locking members 15 are in position to be engaged by the movable locking members 17, which, as shown in Fig.

3, are in the form of hooks pivoted to the section 1 and to an endwise movable rod 18. This rod is connected by a crank arm 19 with a locking hasp 20 on the outside of the trunk section 2 and fixed to a stud 21 rotatably supported in the adjacent wall of the section 2 and extending therethrough, as shown in Fig. 4. This locking mechanism is the same as disclosed in my Reissue 10 Patent No. 14,143, granted May 30, 1916. The locking hasp 20, as in my said prior patent, has a hinged section 22 carrying the key operable tumbler lock mechanism and, in the trunk shown herein, is adapted 15 to engage the socketed plate 23 secured to the lid 3 at one side thereof, as shown.

As an additional lock for the lid 3, I provide a locking device operating in conjunction with the main locking mechanism 20 just described. The lid locking mechanism comprises an endwise movable bar 24 located in the lid 3 between the inner and outer walls thereof, as shown in Fig. 4. Said bar extends across the lid and is slidably mounted in cleats 25, 25. One end of the bar 24 extends into the socketed member 23 and the other end is adapted to project into a recess or space 26 in the lid 3, as illustrated in said Fig. 4. Secured to 30 one of the side walls of the trunk section 2 and projecting upward above the open end thereof is a lug or plate 27 having at its outer end a hole to receive the adjacent end of the locking bar 24. About the latter 35 is coiled a spring 28 bearing at one end against one of the cleats 25 and at the other end against a pin on the bar in a direction constantly urging the bar toward the locking hasp 20. When the hasp is unlocked, 40 the spring 28 moves the bar 24 outward against the hasp, thereby assisting in moving it into open position and at the same time withdrawing its opposite end from the hole in the plate 27, thereby unlocking 45 the lid 3 at that end of the trunk. When the locking hasp 20 is swung into its keeper socket 23, it pushes against the bar 24 and moves its opposite end into the hole in the plate 27, thereby effecting the locking 50 of the lid at opposite sides of the trunk section 2. The lid is thus locked at two points, one by means of the locking hasp 20 at one side of the lid and the other by means of the bar 24 and plate 27 at 55 the opposite side of the lid. This locks the lid 3 securely closed and prevents that corner opposite the locking hasp 20 from springing outward from the trunk, which might happen if there was no locking bar 24 provided for that purpose. Furthermore, the construction enables the trunk sections 1 and 2 to be locked together on turning the hasp 20 to cause the hooks 27 to engage the fixed locking members or eyes 15 60 and at the same time effect the locking of

the lid 3 closed over both of the sections 1 and 2 when the hasp 20 is snapped into locked engagement with its keeper socket 23, all in one operation of locking the trunk and through the operation of one actuating member, namely, the locking hasp 20. This therefore effects the locking of the two sections together at a plurality of points in their length and also effects the locking of the lid 3 closed at two points on 70 opposite sides of the trunk. The lid is unlocked merely by unlocking the hasp 20 from its socket 23 and swinging the hasp outward. The lid may thus be opened while the trunk sections 1 and 2 remain 75 locked by the locking members 15, 17. This is one feature that adapts the trunk for steamship travel, as set forth in my pending application. To unlock the sections 1 and 2, the hasp is turned to the position shown in dotted lines in Fig. 1 to raise the bar 18 and carry the hooks out of the eyes 15, as set forth in my said prior patent.

While I have shown and described herein in detail a trunk locking device constructed in accordance with my invention, it is of course to be understood that the various details of construction illustrated may be variously changed and modified without departing from the spirit and scope of my invention.

I claim as my invention:

1. The combination with a trunk having a body section and a hinged lid section, of a lid locking mechanism, comprising a hinged locking hasp on the outside of one of said sections at one side of the lid, a socket member on the other section and adapted to receive said hasp for locking the lid closed at that side of the same, and means inside of the trunk for locking the lid closed at the side opposite said hasp and actuated on swinging said hasp into and out of said socket.

2. The combination with a trunk having a body section and a hinged lid section, of a lid locking mechanism, comprising a hinged locking hasp on the outside of said body section at one side of said lid, a socket member on said lid and adapted to receive said hasp for locking the lid closed at that side of the same, a fixed locking member on said body section at the opposite side of said lid, a bar slidably mounted in said lid between said socket and said fixed locking member and movable into locking engagement with the latter by said hasp on swinging the same into said socket, and a spring for withdrawing the bar from said fixed locking member on swinging said hasp out of said socket.

3. The combination with a trunk having two hinged together sections, both open at one end, and a lid for closing the open ends

of said sections and hinged to one of the same, of a locking mechanism, comprising means at one side of the trunk for locking and unlocking said sections and for locking 5 and unlocking said lid at that side of the trunk, and means inside of the trunk for locking the lid closed at the side opposite said first mentioned means and actuated through the operation thereof.

10 4. The combination with a trunk having two hinged together sections, both open at one end, and a lid for closing the open ends of said sections and hinged to one of the same, of a locking mechanism, comprising 15 means at one side of the trunk for locking and unlocking said sections, said means including a hinged locking hasp on the outside of one of said sections at one side of the lid, a socket member on the lid and 20 adapted to receive said hasp for locking the lid closed at that side of the same, and means inside of the trunk for locking the lid closed at the opposite side of the same and actuated on swinging said hasp into and 25 out of said socket.

5. The combination with a trunk having two hinged together sections, both open at one end, and a lid for closing the open ends of both of said sections and hinged to one 30 of the same, of a locking mechanism, comprising means for locking and unlocking said sections, said means including a hinged locking hasp on the outside of one of said sections at one side of the lid, a socket 35 member on the lid and adapted to receive said hasp for locking the lid closed at that side of the same, and means including a spring pressed bar carried by the lid for locking the lid closed at the side of the 40 trunk opposite said hasp and actuated on swinging said hasp into and out of said socket.

6. A wardrobe trunk, comprising two hinged together sections, both open at one 45 end, a lid for closing the open ends of said sections and hinged to one of the same, a locking hasp mounted on the outside of one of said sections, a socket secured to the outside of the lid at one side thereof and adapted 50 to receive said hasp for locking the lid closed at that side of the trunk, an endwise movable bar mounted in said lid and

having one end projecting into said socket, a lug secured to the section on which the hasp is mounted and located on the opposite side thereof and having an eye to receive the other end of said bar when the hasp is in said socket, a spring surrounding said bar and acting to constantly force the same toward said socket to withdraw its end 60 from said lug when the hasp is unlocked and swung outward from said socket.

7. The combination with a trunk having two hinged together sections, both open at one end, and a lid for closing the open ends 65 of said sections and hinged to one of the same, of a locking mechanism, comprising means inside of the trunk for locking and unlocking said sections, said means including a hinged locking hasp pivoted on the 70 outside of one of said sections and actuating said means on turning said hasp into and out of position transverse to the length of said trunk, a socket member on the lid and adapted to receive said hasp when in position lengthwise of said trunk for locking the lid closed at that side of the same, and means 75 for locking the lid closed on the opposite side of the trunk and actuated on swinging said hasp into and out of said socket.

8. The combination with a trunk having two hinged together sections, both open at one end, and a lid for closing the open ends of said sections and hinged to one of the same, of a locking mechanism, comprising 80 means inside of the trunk for locking the sections closed, a hinged locking hasp on the outside of the trunk, a socket member on the lid at one side of the trunk and adapted to receive said hasp for locking the lid 85 closed at that side of the same, means for locking the lid closed at the opposite side of the same and actuated on swinging said hasp into and out of said socket, said hasp being connected with the locking means for the 90 sections for actuating the same after being disengaged from said socket, thereby permitting the lid to be locked and unlocked without unlocking the trunk sections.

In testimony that I claim the foregoing 100 as my invention, I affix my signature this 23rd day of August, A. D. 1921.

FRANK W. MEYER.
